FIG. 1

FIG. 3

FIG. 2

FIG. 4

FIG. 5

FIG. 6

In the drawings,

FIGURE 1 is a perspective view of a color comparator for testing the pH of aquarium water and the like showing my new design.

FIGURE 2 is a front view thereof.

FIGURE 3 is a top view thereof.

FIGURE 4 is a side view thereof.

FIGURE 5 is a bottom view thereof.

FIGURE 6 is a rear view thereof.

Both side views are identical.

The vertical shading on the transparent windows represent colored glass.

The broken line indicia illustrated in FIGS. 1 and 2 are shown for illustrative purposes only.

I claim:

The ornamental design for a color comparator for testing the pH of aquarium water and the like, as shown and described.
